Primary Examiner — John R Yeh(74) *Attorney, Agent, or Firm* — TraskBritt(57) **CLAIM**

The ornamental design for a cotter pin assist device, as shown and described.

DESCRIPTION

FIG. 1 is a side perspective view of the cotter pin assist device showing my new design;

FIG. 2 is a bottom view thereof;

FIG. 3 is a side view thereof;

FIG. 4 is another side view thereof;

FIG. 5 is a top view thereof;

FIG. 6 is an end view thereof; and,

FIG. 7 is another end view thereof.

The broken lines in the figures illustrate environment of the cotter pin assist device and form no part of the claimed design.
